SEWING-TABLE.

1,323,745.

Specification of Letters Patent.

Patented Dec. 2, 1919.

Application filed September 7, 1915. Serial No. 49,330.

To all whom it may concern:

Be it known that I, CHARLES W. COFFIN, a citizen of the United States, and resident of Portland, county of Cumberland, State of Maine, have invented an Improvement in Sewing-Tables, of which the following description, in connection with the accompanying drawings, is a specification, like characters on the drawings representing like parts in each of the several views.

This invention relates to tables and while having other and more general fields of usefulness, is well adapted to be embodied in a light readily portable table, preferably with folding legs, designed for use as a sewing table and the like. A prime object of the invention is to provide a table top presenting different portions of its surface with diverse characteristics as to smoothness, hardness, and the like, whereby it is best adapted for uses as a sewing table and in cloth cutting or the like. A further object is to provide an improved construction and relative arrangement of the different portions of the table top whereby they are interfitted and interengaged to constitute a strong and substantial unitary top. The foregoing and other objects and features of the invention will be better understood from the following detailed description taken in connection with the accompanying drawings and will be thereafter pointed out in the appended claims.

Referring to the drawings:

Figure 1 is a perspective view of a table constructed in accordance with my invention;

Fig. 2 is a partial transverse section on line 2—2 of Fig. 3; and

Fig. 3 is a bottom plan view of a table with the legs folded in.

The table is herein shown as having a rectangular oblong top 10, though for purposes of the present invention this is to be considered merely as illustrative. Adjacent the four corners of this top, legs 11 are pivoted as seen at 12 to swing lengthwise of the top for folding in against the underside thereof, the two legs which fold toward each other on the same side from opposite ends of the table being mounted in offset relation so as to lie side by side when folded as indicated in Fig. 2. Each of these legs is held in operative position when extended

by a brace 13 which may be pivoted at 14 to 55 an outer rail of the top and have a notch engageable with a pin on the leg as indicated at 15.

In accordance with my invention the main body portion of the top is formed of light 60 relatively thin material supported and held by a framework composed of a peripheral rail 16 which may be composed of side and end sections dove-tailed at the corners as indicated at 17. The top framework also is provided with an inner rail 18 extending from 65 end to end of the top a short distance from one side thereof which may be considered the front of the top, and a similar lengthwise extending rail 19 extending the length 70 of the top adjacent the back thereof, these rails being secured to the peripheral rail and thus contributing to the strength and 75 rigidity thereof, and of the top. The rails 18, 19 also serve to support at one side the pivot bearings 12 of the adjacent legs, and the braces therefor. The rail 18, however, in the present invention serves a further important function to be now described and for this purpose is shown as somewhat 80 thicker and heavier than the rail 19.

In accordance with my invention the major and rear portion of the table top from end to end is covered with soft cloth presenting a nap surface, or soft felt or the like, 85 as indicated at 20. This cloth or felt is laid upon a backing which may conveniently be of pulp or other like composition made into a stiff board 21, though of course the use of such material is merely illustrative and 90 intended to typify any suitable backing. This board and the cloth laid thereon are held at the back and sides by the peripheral frame 16, resting on a shoulder 22 formed by an undercut recess at the inner top corner 95 of the peripheral rail, and are of course also supported by the rear inner rail 19. The front of the board 21 rests on the rear top portion of the inner rail 18 and may be fastened thereto by suitable securing pins or 100 nails 23. The front of the table top from end to end between the inner rail 18 and the front outer rail is composed of a board 23 preferably presenting a hard 105 smooth surface. The back of this board rests on the front top portion of the rail 18 abutting against the front edge of the board 21. I preferably bring the front edge of the

cloth 20 down between these abutting board edges and extended forward underneath the front edge of the board 23 so that it is caught and securely held as this board is 5 clamped to the rail 18 as by suitable securing screws 24. The front edge of the board 23 is shown as rabbeted at 25 to fit into the undercut recess which forms the shoulder or ledge 22 on the front rail member 16. The 10 rear edge of the hard polished board surface 23 is preferably formed with a measuring scale 26. I have found that this construction of table top is especially convenient and desirable in a sewing table for the reason 15 that the major rear portion of the top, presenting a soft nap surface is noiseless, as shears and other metal utensils are handled and dropped or laid thereon. Further such a surface is highly desirable for the reason 20 that patterns and cloth material being operated on, do not tend to slide thereon so as to be apt to be accidentally displaced, but will adhere and remain in the position where placed, so that such operations as cutting 25 out from patterns is made easier and more convenient. Also perforating or pinking wheels work much better against a relatively soft backing such as here presented. Also the work can be pinned to the cloth or felt 30 surface when required. Still further this soft nap surface makes it much easier to pick up pins, needles and the like than would be the case with a hard smooth surface. On the other hand it is of course requisite and 35 desirable that the front portion of the top adjacent the measure 26, and between it and the front edge, should be smooth, hard and polished so that the material can be readily slid therealong for measuring and cutting 40 purposes. The proportional parts of the top composed of the cloth or nap surface, and of the hard board surface respectively, may be varied as preferred without departing 45 from the essential attributes of the invention, the soft nap surface being preferably of course considerably greater than the smooth hard surface; in practice I preferably make the soft cloth or nap surface to 50 cover somewhat over three-quarters of the area of the board and the smooth board surface somewhat less than one-quarter. However, I desire this as well as other details of 55 construction to be considered as illustrative and not restrictive, reference being had to the appended claims rather than to the fore-

going description to indicate the scope of the invention.

Where I refer in the appended claims to a cloth surface, I intend this, unless otherwise specified, to be understood broadly as 60 including any surface of textile or felt-like material relatively soft and rough as contrasted with the hard smooth surface of the board along the front of the table top.

Having described my invention, what I 65 claim as new and desire to secure by Letters Patent is:

1. A table having a top composed of relatively thin material with a surrounding peripheral rail to support the same, and an inner supporting rail extending from end to end of the table intermediate the sides thereof, said top having a rear portion composed of a backing covered with soft cloth or the like, and a front portion composed 70 of a board presenting a relatively hard smooth surface, said rear and front portions abutting and both resting on said inner rail, the line of division between said front and rear portions extending in parallelism with 75 the front longitudinal edge thereof.

2. A table having a top composed of relatively thin material with a surrounding peripheral rail to support the same, said rail having an under-cut rabbet at its inner top 80 edge receiving the thin material of the body of the top, and an inner rail extending across the top, said top having rear and front portions presenting surfaces with diverse characteristics, the rear portion being 85 sound deadening and the front portion smooth and hard, said portions abutting and both fixed on said inner rail.

3. A table having a top with a rear portion composed of a backing covered with soft cloth or the like, and a front portion composed of a board presenting a relatively hard smooth surface, and an inner rail to which said front and back portions are secured, the cloth of said rear portion being 95 extended under and clamped by the adjacent edge of the board constituting said front portion.

In testimony whereof I have signed my name to this specification in the presence of 105 two subscribing witnesses.

CHARLES W. COFFIN.
